UNITED STATES PATENT OFFICE

129,132

DESIGN FOR A COMBINED TIE CLIP AND NAIL FILE

Dean H. Reynolds, Rochester, N. Y., assignor to
Hickok Manufacturing Company, Inc., Rochester, N. Y., a corporation of New York

Application January 29, 1941, Serial No. 98,513

Term of patent 3½ years

To all whom it may concern:

Be it known that I, Dean H. Reynolds, a citizen of the United States, residing at Rochester, in the county of Monroe and State of New York, have invented a new, original, and ornamental Design for a Combined Tie Clip and Nail File, of which the following is a specification, reference being had to the accompanying drawing, forming part thereof.

In the drawing:

Figure 1 is a front elevation of a combined tie-clip and nail file, in a closed position, showing my new design.

Figure 2 is a side elevation of the same.

Figure 3 is a perspective view of the design in an open position.

Figure 4 is a front end view.

Figure 5 is a rear end view.

Figure 6 is a rear elevation of the nail file element.

Figure 7 is a rear elevation of the scabbard element.

The essential features of my design are shown in full lines.

I claim:

The ornamental design for a combined tie clip and nail file, substantially as shown and described.

DEAN H. REYNOLDS.
